UNITED STATES PATENT OFFICE.

MICHAEL LIPTAK, OF ST. PAUL, MINNESOTA.

HOLLOW FIRE-WALL CONSTRUCTION.

Application filed November 26, 1926. Serial No. 150,942.

This invention relates to improvements in hollow fire walls and has for its objects to provide a wall comprising replaceable sections, the sections being spaced apart to form 5 continuous chambers lengthwise of the wall; to provide such a wall comprising superposed vertically spaced rows of shelf forming headers with pilasters supporting and supported by said headers and interlockingly engaged by their ends with the 10 headers; to provide a hollow fire wall including the headers and pilasters arranged as above mentioned, and further including fire bricks forming the replaceable portion of the wall, 15 and arranged between and upon the headers, and laid in alternate stretcher and header courses; and to provide a hollow wall including the elements above mentioned and in addition including alternate stretcher and 20 header courses, with portions of the header courses projecting beyond the wall to form shelves for receiving stretcher courses which act to protect the end portions of the shelf forming headers and corresponding faces of 25 the pilasters.

Features of the invention include the structure of the wall formed by the use of shelf forming headers in combination with the pilasters supporting the headers; the 30 construction of the shelf forming headers and of the pilasters to co-operate for interlocking engagement to prevent movement of the pilasters; the general combinations and subcombinations of these elements as used 35 in the construction of a hollow fire wall; and the construction of the elements per se.

In the accompanying drawings forming a part of this specification

Figure 1 is a perspective view showing a 40 wall constructed according to the teachings of this invention, and including the buck-stay construction set forth in my copending application Serial No. 140,888, filed October 11th, 1926, for fire walls;

Figure 2 is a plan view, with certain of the wall elements removed to illustrate the arrangement of the wall forming elements;

Figure 3 is a detailed section showing how the buck-stay elements are connected;

Figure 4 is a perspective view with portions of the replaceable wall section removed to show the construction;

Figure 5 is a plan view, enlarged to show the transverse construction of the wall;

Figure 6 is a perspective view of one of the 55 shelf forming header blocks, and means for securing the block to the buck-stay against longitudinal movement;

Figure 7 is a perspective view showing application of the present invention to the 60 formation of a hollow partition wall;

Figure 8 is a perspective view of the shelf forming header used in the construction of Figure 7 and

Figure 9 is a perspective view of the 65 pilaster.

Referring first to Figures 1 and 2. In constructing the wall a footing is first laid, which may be of concrete or masonry, and upon the footing are then laid a series of 70 shelf-forming headers indicated at 5. Each header is provided with projections on opposite sides, the projections being indicated at 10 in Figures 6 and 8. These projections are arranged on opposite sides and extend 75 in the same direction and are arranged to be vertically aligned when the header is in shelf-forming position. The projections ordinarily extend inwardly from each of the opposite end faces in a direction crosswise of the 80 header.

I next arrange the pilasters each of which has grooved ends adapted to interlockingly engage the projections of the shelf-forming headers to prevent displacement of the pilasters. The pilasters are represented at 15, see Figure 9, and the notches or grooves at 16. The pilasters bridge the joint between adjacent abutting headers, and inner end surfaces of the pilasters and the inner end 85 surfaces of the shelf-forming header tile are substantially co-planar as shown. It will be noticed that each end of each pilaster is interlockingly engaged with two shelf-forming headers. In the form of invention shown 90 in Figures 1 to 6 inclusive the pilasters are arranged only at the inner side of the wall. In that form of the invention shown in Figures 7 to 9, inclusive, the pilasters are arranged in rows at each opposite end or at 95 inner and outer sides of the shelf-forming headers. In any event, one of the important features of the present invention is a provision of superposed rows of shelf-forming headers having pilasters supporting and supported by the headers, in which the ends of the headers are interlockingly engaged.

The inner or replaceable wall is built first, 100

because the fire clay mortar is thin, and mortar adjustment can best be made in the outer wall to obtain proper levelling of the headers.

5 Continuing the description of the building of the wall. After the row of pilasters is placed the inner replaceable fire wall facing is built, and this wall comprises alternate stretcher and header courses, the header courses being indicated at 20, and the bricks thereof having portions lying between the pilasters and vertically between the shelf-forming headers and further having portions projecting beyond the wall. The 10 stretcher courses are two bricks deep the inner row 21 of each course extending lengthwise between and having their members abutting the pilasters. The outer stretcher row 22 of each course is arranged 15 to cover the outer surfaces of the pilasters and shelf-forming headers, and since the shelf-forming headers in this instance are approximately the thickness of two fire bricks, two courses of fire bricks, 23, are 20 used as a facing for the ends of the headers, and are supported between those headers 25 which lie respectively upon the top of and against the bottom of a given shelf-forming header. In order to prevent 30 buckling of the wall I use buck-stays 25. An intervening permanent wall section is provided, comprising bricks 26 laid in mortar vertically between the buck-stays. These bricks are herein laid as stretchers 35 between the superposed rows of shelf-forming headers. This portion of the wall is spaced from the replaceable fire brick portion to form the longitudinally extending chambers within the wall. It would be best to have 40 each row of shelf-forming headers supported by buck-stays but in order to cheapen the wall I have shown a construction where intermediate shelf-forming headers are supported by the masonry courses 26. After 45 the wall 26 has been built up upon a row of shelf-forming headers the buck-stay is arranged and its height can be adjusted so that when a course of shelf-forming headers is arranged upon it, the projecting portions 50 of the headers will be at the proper level to engage the depressions 16 of the pilasters to support the inner ends of the headers. I have herein shown a means of connecting the 55 headers to the buck-stays to prevent movement of the header transversely of the wall, this means being illustrated in my copending application, above referred to, and consisting of an opening 30 having a pin 31 therein, the lower end of the pin being imbedded in mortar or cement 32 held in the 60 channel-like buck-stay. This feature forms no part of the present invention. The shelf-forming headers also shown as being notched at the corner as at 33 is properly set forth in my copending application for build- 65

ing unit, Serial No. 138,455, filed September 29th, 1926. This is not a feature of the present invention.

In Figures 7, 8 and 9 a partition wall has been shown, the construction of which is substantially the same as that shown in the first form, except that in this case the wall has replaceable facings one at each side, spaced apart to form the longitudinally extending hollow conduits. 75

In both forms it will be noted that half-brick headers 35 (see Figures 4 and 5) are interposed to cover the portions of the pilasters which lie directly above and below the shelf-forming headers. 80

I claim as my invention:

1. A fire wall comprising superposed vertically spaced rows of shelf-forming headers, pilasters supporting and supported by said headers, and interlockingly engaged by their ends with the headers and fire bricks arranged between and upon the headers to form spaced walls. 85

2. A fire wall comprising superposed rows of shelf-forming headers, pilasters supporting and supported by the headers, said headers and pilasters having complementary projections and depressions interlockingly engaged to prevent displacement of the pilasters, and fire bricks arranged between and upon the headers to form spaced walls. 90

3. A hollow fire wall comprising superposed vertically spaced rows of shelf-forming headers, pilasters supporting said headers and interlockingly engaged by their ends with the headers to prevent displacement of the pilasters, and fire bricks arranged between and upon the headers and laid in alternate stretcher and header courses, portions of the header courses projecting beyond the shelf-forming headers. 100

4. A hollow fire wall comprising superposed rows of shelf-forming headers, one-piece pilasters supported by and supporting the headers, the ends of the pilasters bridging the joints between adjacent abutting headers, and said headers and pilasters being formed for interlocking engagement at the ends of the pilasters to prevent displacement of the latter, and fire bricks arranged between and upon the headers to form spaced walls. 110

5. A hollow fire wall comprising superposed vertically spaced rows of shelf-forming headers, pilasters supporting said headers and interlockingly engaged by their ends with the headers to prevent displacement of the pilasters, and fire bricks laid in alternate header and stretcher courses supported by and filling the space vertically between the shelf-forming headers, certain of the stretcher courses lying between the pilasters and other stretcher courses lying in a position to protect the outer faces of the shelf-forming headers and pilasters. 120

6. A hollow fire wall comprising superposed rows of shelf-forming headers, pilasters between the headers and spaced crosswise thereof to support and be supported by the headers, and having their outer faces flush with the outer faces of the headers, said pilasters being interlockingly engaged by their ends with the headers to prevent displacement, fire bricks arranged between and upon the headers adjacent their outer sides and laid in alternate stretcher and header courses, portions of said header courses projecting beyond the shelf-forming headers, certain of the stretcher courses lying longitudinally between the pilasters and other stretcher courses arranged to protect the outer faces of the shelf-forming headers and pilasters. 70

headers, said pilasters having interlocking connection with said headers, and lying across the joints between adjacent headers, and fire bricks arranged between and upon 5 the headers to form spaced walls.

18. A hollow fire wall comprising a permanent portion composed of longitudinally arranged metallic reinforcing members, shelf-forming headers upon said reinforcing 10 member, pilasters extending between the headers at the inner sides of the headers, said pilasters having interlocking connection with said headers across the joints between adjacent headers, and fire bricks arranged 15 between and upon the headers and laid in alternate stretcher and header courses, certain of the stretcher courses lying between the pilasters and certain other stretcher courses 20 lying in a position to protect the outer faces of the shelf-forming headers and pilasters.

19. A hollow fire wall comprising a per-

manent portion composed of longitudinally arranged metallic reinforcing members, shelf-forming headers upon said reinforcing member, pilasters extending between the 25 headers at the inner sides of the headers, said pilasters having interlocking connection with said headers across the joints between adjacent headers, the inner vertical faces of pilasters and headers being substantially co-planar, and fire bricks arranged between and upon the headers and laid in alternate stretcher and header courses, certain of the stretcher courses lying between the pilasters and certain other stretcher 30 courses lying in a position to protect the outer faces of the shelf-forming headers and pilasters. 35

In witness whereof, I have hereunto set my hand this 24th day of November 1926.

MICHAEL LIPTAK.
